UNITED STATES PATENT OFFICE.

LESLIE HOPPER PITZER, OF PRATT, KANSAS.

BUSHING EXTRACTOR AND REMOVER.

Application filed June 20, 1921. Serial No. 478,845.

To all whom it may concern:

Be it known that I, LESLIE HOPPER PITZER, a citizen of the United States, residing at Pratt, in the county of Pratt, State of Kansas, have invented a new and useful Bushing Extractor and Remover; and I do hereby declare the following to be a full, clear, and exact description of the invention, such as will enable others skilled in the art 10 to which it appertains to make and use the same.

The invention relates to bushing removers and replacers and has for its object to provide a device of this character by means of 15 which bushings may be easily removed and replaced.

A further object is to provide a bushing remover and replacer particularly adapted for removing bushings from pistons of internal combustion engines in such a manner 20 as not to bend or break the pistons.

A further object is to provide a bushing remover and replacer adapted to be used in connection with pistons of internal combustion engines and comprising a standard, the upper end of which is provided with a chambered member adapted to engage the boss of a piston adjacent the bushing disposed therein, and to provide a punching element carried by a member pivoted to the standard, which member is forced inwardly through a leverage connection between the standard and the pivoted member.

With the above and other objects in view 35 the invention resides in the combination and arrangement of parts as hereinafter set forth, shown in the drawings, described and claimed, it being understood that changes in the precise embodiment of the invention may 40 be made within the scope of what is claimed without departing from the spirit of the invention.

In the drawings:—

Figure 1 is a side elevation of the bushing 45 remover showing a conventional form of piston held therein for removing the bushing therein.

Figure 2 is a top plan view of the bushing remover showing the same with the 50 bushing punch removed.

Figure 3 is a detail sectional view through a portion of the punch carrying arm and a portion of a piston and its bushing.

Figure 4 is an end view of the bushing 55 punch.

Referring to the drawings, the numeral 1 designates a standard which may have its lower end 2 disposed in a vice or in any other suitable holding means. Removably disposed on the upper end of the standard 1 is a collar 3, which collar when piston 4 is placed on the upper end of the standard 1 engages the boss 5 of the piston adjacent the bushing 6 which is to be removed by the bushing remover in such a manner as not to 60 bend or break the piston 4 which is of light construction and easily bent or broken. Extending outwardly from the lower end 2 of the standard 1 are arms 7, between the rear ends of which an upwardly extending arm 8 is pivoted at 9. Detachably secured to the upper end 10 of the pivoted arm 8 is a punch 11, which punch is substantially in axial alignment with the collar 3 carried by the standard 1, and is provided with a reduced 70 portion 12 which enters the bore of the bushing 6 and with an enlarged portion 13 there-by forming a shoulder for engaging the outer end of the bushing 6 in such a manner that when the arm 8 is forced inwardly said 80 bushing 6 will be forced inwardly until it is removed from the piston 4. It is obvious that when it is desired to replace the bushing that the same can be replaced by substantially the same operation. 85

Secured to the pivoted arm 8 is a rear-wardly extending U-shaped bracket 12^a between the arms of which is pivotally mounted as at 13^a an operating lever 14, by means of which lever the pivoted arm 8 is forced 90 in the direction of the standard 1, during a bushing removing operation. Pivotally secured at 15 to the arm 16 of the lever 14 are forwardly and downwardly extending arms 17, which arms have their forward 95 ends pivotally connected to transversely disposed bolts 18 substantially in the same horizontal plane as the pivotal point 13^a. The arms 17 are pivoted to the standard 1 in relation to the pivotal point 13^a in such 100 a manner that during a bushing punching operation the punch 11 will remain in substantially axial alignment with the collar 3 thereby insuring the proper punching of the bushing from its bearing. 105

From the above it will be seen that a bushing punch is provided which is simple in construction and one particularly adapted for use in connection with bushings of pistons of internal combustion engines. 110

2
The invention has been described and illustrated for use in connection with pistons of internal combustion engines, however, it is to be understood that the device may be used in connection with any machinery wherein it is necessary to remove the bushing and replace the same.

The invention having been set forth what is claimed as new and useful is:

- 10 1. A bushing remover comprising a standard, an arm carried by said standard and pivoted thereto, a collar carried by the standard and adapted to engage an article adjacent a bushing therein, a punching element carried by the pivoted arm and adapted to engage the bushing; and lever means whereby said pivoted arm may be forced in the direction of the standard for punching a bushing from its bearing.
- 15 2. A bushing remover comprising a standard, an arm carried by said standard and pivoted thereto; a collar carried by the standard and adapted to engage an article adjacent the bushing to be removed, a punching element carried by the upper end of the arm pivoted to the standard and adapted to be forced into engagement with one end of a bushing for forcing said bushing through the collar carried by the standard; a rearwardly extending arm carried by
- 20 the pivoted arm at a point intermediate its ends, an operating lever pivoted to the rearwardly extending arm, and a forwardly and downwardly extending arm pivoted to the operating lever at one of its ends and to the standard at its forward end at a point in substantially the same horizontal plane as the pivotal point of the operating lever.
- 25 3. The combination with an internal combustion engine piston having a wrist pin bushing therein, said bushing extending through a boss extending inwardly from the side wall of the piston, of a bushing remover therefor, said bushing remover comprising a pair of arms pivotally movable in relation to each other, one of said arms being provided with a collar of greater diameter than the bushing and adapted to engage the boss surrounding the bushing; a punching element carried by one of said arms and positioned to engage the outer end of the bushing; and lever means whereby said arms may be forced toward each other.

In testimony whereof, I have signed my name to this specification in the presence of two subscribing witnesses.
